UNITED STATES PATENT OFFICE

2,155,070

HUMIDIFIER

William J. Woolley, Chicago, Ill.

Application August 13, 1937, Serial No. 158,962

4 Claims. (Cl. 126—113)

This invention relates in general to automatic humidifiers, and more particularly to such a device which is adapted for use in hot air furnaces.

A principal object of the invention is the provision of an automatic humidifier having an adjustable hood portion which permits it to be mounted in the dome portion of a hot air furnace regardless of the particular slope of the side wall of the furnace dome.

Another important object of the invention is the provision of such a humidifier having means for guiding the hot air over the water surface, which particularly adapts it for use in a forced circulation system.

A further important object of the invention is the provision in such a humidifier of means for adjusting the position of the water pan to vary the evaporating capacity thereof.

Another object of the invention is the provision of pan overflow discharge means forming a part of the pan evaporating capacity adjusting means.

A further object of the invention is the use of a water pan of sheet bronze construction which increases the rate of evaporation, because of its high co-efficient of heat transmission.

Numerous other objects and advantages of the invention will be apparent as it is better understood from the following description, which, when taken in connection with the accompanying drawings, discloses a preferred embodiment thereof.

In the drawing,

Figure 1 is a perspective view of an automatic humidifier embodying the features of the instant invention shown installed in the hood of a hot air furnace with part of the wall of the latter broken away;

Fig. 2 is a side elevational view of the humidifier of Fig. 1;

Figs. 3, 4 and 5 are vertical sectional views taken substantially on the lines 3—3, 4—4 and 5—5, respectively, of Fig. 2; and

Fig. 6 is a vertical sectional view taken substantially on the line 6—6 of Fig. 5.

Referring more particularly to the drawing, reference numeral 11 indicates generally a hot air furnace of any desired type and having the usual dome or hood portion 12 at its upper end. A humidifying device, indicated generally by reference numeral 13, is adapted to be mounted in the hood 12 of the furnace, and comprises a pan 14 and an automatic feeding device 15 for supplying water thereto.

The automatic water feeder 15 is similar in

internal construction to that disclosed in applicant's U. S. Letters Patent No. 2,079,098, issued May 4, 1937, having inlet and outlet compartments therein with a float controlled valve communicating therebetween. A supply tube 16 is connected at its lower end to the upper end of the feeder 15 to communicate with the inlet compartment therein, and is connected in any suitable manner at its upper end to a water pipe 17. The supply pipe 16 is preferably formed of copper tubing, but any other suitable material may be employed. An inlet conduit 18 is connected at one end in any desired manner to the lower end of the feeder 15 to communicate with the outlet compartment therein, and is connected at its other end to the forward end of the pan 14. The inlet conduit 18 is also preferably formed of copper tubing, but any other suitable material may be employed. An equalizer pipe and brace 19 interconnects the pan 14 and the upper portion of the outlet compartment within the water feeder 15.

The water pan 14 is preferably stamped from sheet bronze, and is provided with front and rear end plates 21 and 22, respectively, which are made of brass or any other desired material, and are secured to the body portion of the pan in any suitable manner. The bottom wall of the pan 14 is formed with a longitudinal groove or rib 24 (Fig. 4), and the side walls are provided with a plurality of circumferential grooves or ribs 25 to insure a rigid construction.

A plurality of upstanding bracket members 26 are secured at spaced intervals at their lower ends to the marginal edges of the body portion of the pan 14. The bracket members 26 are bent inwardly at their upper ends, as indicated at 27 in Fig. 4, and are provided with suitable apertures in which are mounted hinge rings 28. The rings 28 also engage suitable apertures provided adjacent the inner marginal edge portions of a pair of curved, longitudinally disposed wing members 29. The wings 29, in their outward or operative position of Figs. 1, 2 and 4, are adapted to force or guide the rising currents of warm air over the surface of the water in the pan 14 and into direct contact therewith. The purpose of the hinges 28 is to permit swinging or folding of the wings 29 to an inner or inoperative position over the pan 14 (as shown in broken lines in Fig. 4) to facilitate insertion and withdrawal of the pan into and out of the hood 12 of the furnace 11. The width of the wings 29 is such as to permit their being nested

one above the other in this folded or inoperative position.

The pan 14 having been inserted within a suitable small aperture in the side wall of the hood 12 of the furnace 11, such aperture is sealed or closed off by a lower bonnet plate 31 and an upper bonnet hood member 32, as shown in Fig. 1. The bonnet plate 31 is substantially U-shaped so as to closely conform to the outer surface of the pan 14 adjacent the forward end wall 21 thereof. The leg portions of the bonnet plate 31 are provided with slots 33 through which bolts 34 or other suitable holding means are adapted to extend to secure the plate to the side wall of the furnace hood 12. The bonnet hood 32 is provided with a centrally disposed, outwardly extending dome portion 35 which is adapted to engage the forward end of the pan 14 adjacent the lower edge thereof. The bonnet hood 32 is also provided with a pair of downwardly extending leg portions 36 which are bent forwardly out of the plane of the marginal portion thereof and are adapted to overlap the leg portions of the plate 31. The bolts 34 extend through suitable apertures in these leg portions 36, and additional rivets, screws, or the like, 37 may be employed to rigidly secure the members 31 and 32 to the side wall of the furnace hood 12. From the above description, it will be readily apparent that the plate 31 and hood 32 constitute adjustable means for effectively sealing the small aperture in the side wall of the furnace hood 12 through which the pan 14 has been inserted, regardless of the particular slope of the side wall of the furnace hood 12.

An overflow pipe and rigid supporting brace 41 is secured in any suitable manner to the rear end plate 22 of the pan 14 to provide a leak-proof joint therebetween, and is of sufficient length to extend outwardly through and beyond the wall of the furnace dome 12. A suitable aperture 42 (Fig. 1) is provided in the wall of the furnace dome 12 for this purpose. A plate 43 is adapted to be secured in any suitable manner to the outer surface of the wall of the furnace dome 12, and is provided with a vertically disposed slot 44 which is positioned in alignment with the aperture 42. The slot 44 (Fig. 5) is enlarged at 45 at its center and end portions. The width of the narrow part of the slot 44 is substantially equal to the outer diameter of the overflow pipe 41, which pipe extends outwardly therethrough. An adjustable cover plate 46 is slidably mounted upon the overflow pipe 41, and is adapted to be resiliently held against the outer surface of the plate 43 by a spring 47 which surrounds the pipe 41 and is retained at its outer end by an adjustable collar 48. The plate 46 is provided with an inwardly extending annular flange 49 (Figs. 5 and 6) surrounding the pipe 41 and in sliding engagement therewith which is adapted to engage one of the enlarged portions 45 of the slot 44 in the plate 43.

It will thus be apparent that, if the plate 46 is slid outwardly on the pipe 41 relative to the plate 43 against the tension of the spring 47, the pipe 41 may be moved vertically relative to the furnace dome 12, and that it will be retained in any one of three selected positions by the engagement of the flange 49 with one of the enlarged portions 45 of the slot 44 of the rigidly secured plate 43. Such vertical movement of the plate 46 relative to the plate 43 is guided by a pair of vertical slots 51 (Fig. 5) in the plate 46

engaging a pair of outwardly extending lugs 52 formed on the plate 43.

It will be apparent from the above description, that the water pan 14 may be readily mounted within the dome of a hot air furnace of any particular construction, the adjustable bonnet plates 31, 32 and the adjustable cover plates 43, 46 being adapted to compensate for variations in slope in the side walls of the furnace dome. The pan 14 having been inserted in the furnace dome, the wings 29 are swung to their outward or operative position as shown in Fig. 1. The rising currents of warm air within the furnace are guided by these wings 29 over and into contact with the surface of the water in the pan 14. The feeder 15 functions to automatically maintain the water level in the pan 14 constant. The rate of evaporation of this water from the pan 14 may be varied by adjusting the level of the pan through the agency of the overflow pipe 41 and the members 20 43 to 52. This results in the maintenance of a lesser or greater amount of water in the pan 14. The use of sheet bronze in constructing the pan 14 and the provision of the wings 29 greatly increases the rate of evaporation over that obtainable by humidifying devices of the prior art. The wings 29 are particularly adapted for use when the humidifying device is employed in a hot air furnace having forced circulation, since in such an installation, the air currents normally pass 25 by the evaporating pan very rapidly, and the wings will insure the warm air coming into direct contact with the water to be evaporated.

It is thought that the invention and many of its attendant advantages will be understood 35 from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an automatic humidifier for use in hot air furnaces or the like, having a water pan 45 adapted to be mounted in the furnace; means for selectively adjusting the vertical position of one end of said pan from the exterior of the furnace to vary the capacity of the pan, comprising a plate mounted on the furnace and having an elongated vertical slot therein, said slot being enlarged at different points along its length to provide spaced apertures of greater width than the slot, a supporting member of lesser width than said slot and secured to one end of said water pan and extending through said slot, a retaining member slidably mounted on said supporting member exteriorly of the furnace and having a portion thereof of greater width than said slot and adapted to engage a selected one of said apertures, and means for resiliently maintaining said portion of the retaining member in a selected aperture in said plate.

2. In combination with a hot air furnace or the like having a dome portion with an aperture in a side wall thereof, a humidifying device, comprising a water pan adapted to be inserted through said aperture into the dome portion of said furnace and mounted therein in the path of warm air currents generated by the furnace, and means 65 mounted on said pan for movement relative thereto between operative and inoperative positions and adapted in operative position to extend outwardly from said pan to direct the flow of warm air currents into the pan, said means 70 75

being so constructed and arranged as to be positioned between the vertical planes of the side portions of said pan when in inoperative position to facilitate the insertion and withdrawal of said pan through said aperture.

5. 3. In combination with a hot air furnace or the like having a dome portion with an aperture in a side wall thereof, a humidifying device, comprising a water pan adapted to be inserted 10 through said aperture into the dome portion of said furnace and mounted therein in the path of warm air currents generated by the furnace, and a pair of wing members hingedly connected to said pan for movement between operative and 15 inoperative positions, said wing members in operative position extending laterally from said pan to direct the flow of warm air currents into the pan and in operative position being dis-

posed between the vertical planes of the side portions of said pan to facilitate the insertion and withdrawal of said pan through said aperture.

4. In a humidifying device for use in hot air furnaces or the like, a water pan adapted to be mounted in the path of flow of warm air currents generated by said furnace, and curved wing members mounted on each side of said pan in spaced relationship to the marginal edges thereof and extending laterally therefrom for directing the 10 warm air currents into said pan and into contact with the surface of the water therein, said wing members being so constructed and arranged as to be moved from extended position to folded position one above the other between the vertical 15 planes of the side marginal edges of the pan.

WILLIAM J. WOOLLEY.
